POLISH KIT

Filed Sept. 11, 1961

thereby, said can being of a depth less than said sleeve, and a polish cloth disposed over said sleeve and can, said top panel engaging said polish cloth and maintaining the same in sealing engagement with said sleeve, whereby when said removable insert is removed from said casing said can of polish is ready for immediate use.

2. In combination, a polish kit comprising a casing, a foldable paste polish can holder disposed in and removable from said casing, said holder including means for holding a resilient sleeve, a resilient sleeve in said holder engaged by said holding means, a can of paste polish within said resilient sleeve maintained therein by engagement therewith, said can being without a top, and means substantially sealing said can when said holder is in folded position.

3. In combination, a polish kit comprising a casing, and a foldable removable insert in said casing comprising a paste polish holder including a resilient sleeve of a depth substantially that of a can of paste polish, means supporting said sleeve with one end closed, a can of paste polish within said sleeve in frictional engagement therewith, removable means closing the other end of said

sleeve to substantially seal the area occupied by said can of paste polish, and movable means maintaining said removable means in position while said insert is in said casing.

5. 4. In combination, a polish kit comprising a casing, and a foldable removable insert in said casing comprising a paste polish holder including a resilient sleeve of a depth substantially that of a can of paste polish, means supporting said sleeve with one end closed, a can of paste polish within said sleeve in frictional engagement therewith, said can of paste polish having the top removed, removable means closing the other end of said sleeve to substantially seal the area occupied by said can of paste polish, and movable means maintaining said removable means in position while said insert is in said casing.
